[57] CLAIM

The ornamental design for a bottle, as shown and described.

DESCRIPTION

FIG. 1 is a front elevational view of a bottle showing our new design, the rear elevational view is a mirror image thereof;

FIG. 2 is a side elevational view of the bottle as seen from the right side of FIG. 1, the left side being a mirror image thereof;

FIG. 3 is a top plan view of the bottle shown in FIG. 1; FIG. 4 is a bottom plan view of the bottle shown in FIG. 1;

FIG. 5 is a fragmentary sectional view taken along line 5—5 of FIG. 4;

FIG. 6 is a front elevational view of a second embodiment of the bottle, the rear elevational view is a mirror image thereof;

FIG. 7 is a side elevational view of the bottle as seen from the right side of FIG. 6, the left side being a mirror image thereof;

FIG. 8 is a front elevational view of a third embodiment of the bottle, the rear elevational view is a mirror image thereof; and

FIG. 9 is a side elevational view of the bottle as seen from the right side of FIG. 8, the left side being a mirror image thereof.

The top plan, bottom plan, and sectional views of the bottles shown in FIGS. 6-9 are the same as are shown in FIGS. 3, 4, and 5, respectively.
